TETRAALKYL LEAD ANTIKNOCK BLENDS
 Edmund L. Niedzielski, Wilmington, Del., assignor to
 E. I. du Pont de Nemours and Company, Wilmington,
 Del., a corporation of Delaware
 No Drawing. Filed Mar. 15, 1962, Ser. No. 180,918
 7 Claims. (Cl. 44—69)

This invention is directed to tetraalkyl lead antiknock blends for gasoline comprising tetraalkyl lead antiknock agents and organic halogen compounds. More particularly, the present invention is directed to the use in such compositions of organic halogen compounds which under conditions of storage are highly compatible with the alkyl lead antiknock compound, and which under conditions of use in high octane number aromatic blend gasolines significantly enhance the antiknock value of the alkyl lead antiknock compound while at the same time act efficiently as scavenging agents for the lead products of combustion.

Tetraalkyl lead antiknock compositions are widely used to improve octane ratings of fuels for high compression Otto cycle engines. These compositions consist essentially of the organolead antiknock agents and at least one organic halogen compound that is a scavenger for lead in the combustion process. Practically speaking, the scavenger material should be miscible and compatible with the tetraalkyl lead compound, forming therewith a homogeneous, normally liquid storage-stable product, and in use it should have no harmful effect on the antiknock properties of the alkyl lead component. However, many such organic halogen compounds lack these properties. They are in general reactive towards tetraalkyl lead, forming haze and insoluble matter under storage conditions, as disclosed, for example, in U.S. 2,722,477 and in U.S. 3,005,780. In addition, as a class, these organic halogen compounds tend to be antagonistic to the antiknock property of the alkyl lead, particularly at high concentrations, as disclosed by Livingston, "Antiknock Antagonists," Industrial and Engineering Chemistry, vol. 43, pages 663-664 (1951). While the art describes many organic halogen compounds that are lead scavengers, in commercial practice ethylene dichloride and ethylene dibromide are normally used.

The quantity of ethylene dichloride and ethylene dibromide used is dependent upon the theory of halogen atom to lead atom. Thus, 1.0 theory of halogen is defined as the quantity theoretically required for reaction of the halogen with the lead to form the lead halide, which quantity is two atoms of halogen per atom of lead. Thus, for aviation use a quantity of ethylene dibromide is used which would give, per atom of Pb as tetraalkyl lead, two atoms of Br as ethylene dibromide (1.0 theory). While, for automotive use, as described, for example, in U.S. 2,398,281, a quantity of ethylene dibromide and ethylene dichloride is used which would give, per atom of Pb as tetraalkyl lead, one atom of Br as ethylene dibromide (0.5 theory) plus 2 atoms of Cl as ethylene dichloride (1.0 theory).

It is also known that hydrocarbon fuels of the gasoline boiling range that contain relatively large proportions of aromatic hydrocarbons respond rather poorly (relative to paraffinic hydrocarbons) to the knock suppressing potential of tetraalkyl lead antiknock agents. Recently it has been found that certain volatile organic substances (including carboxylic acids, their anhydrides and esters) are appreciators of organolead antiknock activity in the high octane number aromatic type fuels, enhancing the effectiveness of the antiknock agent. However, introduction of halogen substituents into such appreciators has been observed to exert a marked depreciating effect. For example, Australian patent application 42,139/58 discloses

2

that monochlorotacetic acid and 2-chloropropionic acid among others are without antiknock effect or are actually harmful in leaded fuel. It should be noted in this connection that antiknock improvements realized by means of

5 alkyl lead antiknock appreciators often are of the order of a fraction of an octane number, unless rather large amounts of material are used. Such increases while appearing numerically small are nevertheless significant, particularly at the 100 octane number and greater level, 10 in view of the technical difficulty and high cost of achieving increased fuel quality by hydrocarbon refining methods and by use of additional amounts of the conventional organometal antiknock agents. For example, adding a 15 4th ml. of tetraethyl lead per gallon of aromatic gasoline as herein contemplated and already containing 3 ml. tetraethyl lead per gallon, and which leaded fuel has a Research Method octane rating of about 100, increases the knock rating about 1 octane number.

It is, therefore, an object of this invention to provide 20 novel fuel compositions.

It is another object of this invention to provide new 25 and novel homogeneous liquid storage stable tetraalkyl lead antiknock blends comprised essentially of the tetraalkyl lead and one or more organic halogen scavengers for lead.

It is still another object to provide novel blends of 30 gasoline wherein the organic halogen scavenger component provides the property of appreciating the antiknock effect of the tetraalkyl lead in high octane number aromatic type gasolines as well as the property of scavenging lead in the combustion process.

These and other objects will be apparent in the following 35 description and claims.

More specifically, the present invention is directed to 40 a tetraalkyl lead antiknock-lead scavenger blend comprising essentially a tetraalkyl lead and from about 0.2 to 1.0 theory of chlorine as a trichloromethyl substituted organic ester having the formula $\text{Cl}_3\text{C}-\text{C}(\text{R})_2-\text{O}-\text{Ac}$, where R is a C_1-C_2 alkyl and Ac a C_1-C_3 acyl radical.

The present invention is also directed to a motor fuel 45 composition comprising a mixture of hydrocarbons in the gasoline boiling range of which at least 15% by volume are aromatic hydrocarbons of the character of those occurring in catalytically cracked and reformed gasolines, and which mixture of hydrocarbons has an octane rating of at least 80 as measured by the ASTM Research Method (D-908-59), an antiknock quantity of a tetraalkyl lead antiknock agent and from 0.2 to 1.0 theory of a trichloromethyl substituted organic ester having the 50 formula $\text{Cl}_3\text{C}-\text{C}(\text{R})_2-\text{O}-\text{Ac}$, where R is a C_1-C_2 alkyl and Ac a C_1-C_3 acyl radical.

This invention is based on the discovery that (1) blends 55 of tetraalkyl lead antiknock such as tetraethyl lead (TEL) with a trichloromethyl substituted organic ester such as 1,1,1-trichloro-2-methyl-2-propyl acetate, viz. $\text{Cl}_3\text{C}-\text{C}(\text{Me})_2-\text{O}-\text{COMe}$, shows greater storage stability than the comparable commercial blends of TEL with ethylene dichloride and ethylene dibromide and (2) such blends, when used in high octane number aromatic 60 gasolines as herein described, provide greater improvements in the knock resistance of the fuels than obtained with TEL alone or in combination with the conventional ethylene dihalide scavengers.

Under conditions ordinarily encountered in the handling, 65 shipping and storing of commercial blends, the blends of the present invention remain clearer and more free of haze and sediment for significantly longer periods of time. In contrast, the use of an isomeric trichloromethyl substituted ester, namely, tert-butyl trichloroacetate, viz. $\text{CCl}_3\text{CO}_2\text{C}(\text{Me})_3$, results in highly unstable blends with respect to the formation of haze and insoluble matter. The significant improvement in the antiknock

performance of the blends of this invention is attributed to the appreciating effect of the trichloromethyl substituted ester component. Such results are surprising in view of the fact that they are obtained with relatively small amounts (less than 0.1 volume percent based on the gasoline) of the chloro compound. The prior art on appreciators for alkyl lead compounds, for example the Australian appln. 42,139/58 heretofore referred to, discloses that there is no beneficial effect when the concentration of the appreciator is below 0.1 volume percent of the gasoline.

The organolead antiknock employed in the practice of the present invention may be any of those known to the art for such purpose, but usually will be a lower tetraalkyl lead, e.g., methyl triethyl lead, tetraethyl lead, tetramethyl lead, dimethyl diethyl lead, trimethyl ethyl lead, tetraisopropyl lead, and the like, and mixtures of any two or more of such organolead antiknock agents. The organolead antiknock agent will be employed in an antiknock quantity, usually in the proportion of from about 1 to 4 grams of Pb for each gallon of the motor fuel, and preferably at concentrations of from about 2 to 3 grams Pb per gallon of fuel. The chloro-substituted esters are lower alkanoic esters of trichloromethyl dialkyl carbinols having the formula $\text{CCl}_3-\text{C}(\text{R})_2-\text{OH}$, R being methyl or ethyl, exemplified by the formate, acetate and propionate of chloroetone, $\text{CCl}_3\text{C}(\text{Me})_2\text{OH}$. They are conveniently made by acylating such carbinol as chloroetone with the appropriate acid chloride as known to the art. As starting carbinol, homologs of chloroetone may also be used such as those obtained by carbonyl addition of chloroform to methyl ethyl ketone or diethyl ketone, and mixtures of the alcohols and mixtures of the acids may be employed in the acylating reaction to produce mixtures of esters of the formula $\text{CCl}_3-\text{C}(\text{R})_2-\text{O}-\text{Ac}$, where R=methyl or ethyl or both and Ac stands for one or more acyl radicals of the C_1-C_3 alkanoic acids. 1,1,1-trichloro-2-methyl-2-propyl acetate is particularly preferred.

The trichloromethyl-containing esters are normally liquid, miscible with tetraalkyl lead antiknock compounds, soluble in hydrocarbon solvents, and insoluble in water. They may be employed alone as the sole scavenger or in combination with other known organic halogen compounds that are scavengers for lead in combustion processes. In general there may be employed 0.5 to 1.0 theory chlorine as a trichloromethyl-containing ester and from 0.5 to 1.5 theories of halogen in the form of chloro- and bromohydrocarbon scavenging agents, with generally not more than about 0.5 theory of the total halogen being bromine. Preferably, in the practice of this invention, the trichloromethyl-containing esters are used with one or more ethylene dihalide scavenger, e.g., ethylene dichloride, ethylene dibromide, or ethylene chlorobromide. In the formulation of antiknock blends, the trichloromethyl-containing esters may be added to the conventional Motor Mix formulation (0.5 theory bromine as ethylene dibromide and 1 theory chlorine as ethylene dichloride) or they may replace part of the other halogen compounds to the extent of 0.2 to 1 theory halogen (preferably 0.5 to 1 theory) as defined above. For example, the scavenging formulation may consist of 0.5 theory chlorine as chloro-ester, 0.5 theory chlorine as ethylene dichloride, and 0.5 theory bromine as ethylene dibromide; or it may consist of 0.5 theory chlorine as chloro-ester and 1.0 theory chlorine as ethylene dichloride. Normally the total halogen content (including that provided by the other halogen compounds) will correspond to at least 1.0 and not exceed 2.5 theories.

In connection with the heretofore described use of alkyl lead appreciators in amounts of at least 0.1 volume percent of the fuel, it should be noted that at the normal antiknock use level of 1 to 4 grams of Pb/gal. of fuel that 1.0 theory halogen of any of the compounds contemplated herein corresponds to about 0.07 volume percent or less of the gasoline.

The mixture of hydrocarbons which constitute the principal component of the fuel compositions utilized in the practice of this invention may be a commercial gasoline containing the aromatic hydrocarbons in the herein described amounts or it may be a blend of hydrocarbons of the character of those present in such gasolines. Thus, for example, it may be a catalytic-cracked stock, a catalytic-reformed stock, or blends of one or more of these cracked and reformed stocks, or blends of one or more of the heretofore described stocks with saturated stocks such as the synthetic alkylates and straight run stocks.

Typical aromatic hydrocarbons which are essential components of the motor fuels of this invention, and which are of the character of these aromatic hydrocarbons which are produced in catalytic cracking and catalytic reforming operations, are the mono- and poly-lower alkyl benzenes such as toluene, ethylbenzene, the xylenes, and the like.

Typical catalytic-cracked refining stocks which may be utilized in the practice of the present invention contain from about 6 to about 25 volume percent aromatic hydrocarbons, about 29-44 volume percent olefins, the rest saturated hydrocarbons. Catalytic-reformed stocks run higher in aromatics, usually 40-70 volume percent, and are lower in olefins. Synthetic alkylates are essentially saturated hydrocarbons, high in isoparaffins. Stocks such as these are blended in various proportions for the production of commercial fuels for spark ignition engines. These fuels normally boil within the range of about 80° F. to about 440° F. Blended fuels for commercial use, such as those for automotive use, contain on the average up to about 55 volume percent aromatic-, up to about 30 volume percent olefinic-, the rest saturated hydrocarbons.

The motor fuels of the present invention contain at least 15 volume percent, more usually at least 20 volume percent, and not more than about 75 volume percent aromatic hydrocarbons. Olefinic hydrocarbons are not essential and may be present in the normally occurring proportions. Preferably the fuels will contain at least about 25 volume percent aromatics and less than 30 volume percent olefins.

Preferably also, the base fuels will be of high quality with respect to knock resistance, having a knock rating at least 80 as measured by the ASTM Research Method.

The motor fuels may also contain other additives normally associated with the finished gasolines, such as antioxidants, metal deactivators, dyes, detergents, antiicing agents, ignition control additives such as phosphorus compounds, and the like.

Representative examples illustrating the present invention follow:

EXAMPLE 1

Tetraethyl lead antiknock blends are formulated by mixing the individual components in the proportions tabulated below. Each, a clear homogeneous mixture, is placed together with a 1020 stainless steel coupon in a 4 oz. glass jar to about the $\frac{1}{3}$ -full level under air. The jars are capped and stored at room temperature (25° C.) in the dark. Periodically they are examined visually with the results noted below.

Table I.—Storage-stability of TEL antiknock blends

[Scavenger: 1.0 theory ethylene dichloride plus 0.5 theory of halogen as co-scavenger]

Blend	Co-Scavenger	Observation on Blend
(A) -----	1,1,1-trichloro-2-methyl-2-propyl acetate.	Essentially unchanged after 3 weeks; no haze, no rusting.
(B) -----	t-Butyl trichloroacetate.	Gelatinous precipitate after one day.
(C) -----	Ethylene-dibromide.	Considerably darkened after 2 weeks; blend hazy and metal rusted.

The comparison shows that Blend A illustrating this invention is significantly more storage-stable than the con-

ventional Motor Mix proportions represented by Blend C. Blend B, containing an isomeric trichloroester not of this invention, is decidedly inferior in storage stability, the t-butyl trichloroacetate evidently being reactive towards tetraethyl lead.

EXAMPLE 2

An aromatic gasoline consisting of 48 volume percent aromatic hydrocarbons, 12 volume percent olefinic hydrocarbons and 43 volume percent saturated hydrocarbons, and showing 10% evaporation at 134° F., 50% at 250° F. and 90% at 308° F. in the ASTM distillation test (D-86-56), is leaded to contain 3 ml. TEL/gal. along with scavenger material as indicated below. The Research Method octane rating of the fuel containing the TEL without scavenger is 101.8. The effect of the scavenger composition on this octane rating is expressed below in terms of octane number change.

Table II.—Effect of scavenger composition on octane rating of leaded high aromatic gasoline

[TEL Conc.=3 ml./gal.]

Test	Scavenger	Change in O.N. (Research)
(1)-----	1.0 theory ethylene dichloride plus 0.5 theory ethylene dibromide.	-0.1
(2)-----	1.5 theories ethylene dichloride-----	0.0
(3)-----	1.0 theory ethylene dichloride plus 0.5 theory 1,1,1-trichloro-2-methyl-2-propyl acetate.	+0.2

EXAMPLE 3

An aromatic gasoline consisting of 34 volume percent aromatic hydrocarbons, 23 volume percent olefins and 43 volume percent saturated hydrocarbons, and having a leaded Research Method octane rating of 99.3 when leaded with 3 ml. TEL/gal. as Motor Mix, is treated to contain 3 ml. TEL/gal. together with 1.0 theory chloride as ethylene dichloride and 0.5 theory additional chlorine as 1,1,1-trichloro-2-methyl-2-propyl acetate. The leaded Research Method octane number is 99.5 (0.2 octane number increase).

An increase of 0.3 octane number is obtained, on comparing the same scavenger systems in the same gasoline, when instead of tetraalkyl lead there is used a mixture of tetraalkyl lead as follows in an amount providing 3.1 grams of Pb/gal. of the fuel: 6.25 mole percent tetramethyl lead, 25 mole percent trimethylethyl lead, 37.5 mole percent dimethyldiethyl lead, 25 mole percent methyltriethyl lead, and 6.25 mole percent tetraethyl lead.

1,1,1-trichloro-2-methyl-2-propyl acetate may be replaced with substantially the same results in any of the preceding representative examples by any one or more of the following trichloromethyl substituted esters in the practice of this invention: 1,1,1-trichloro-2-methyl-2-propyl formate, 1,1,1-trichloro-2-methyl-2-propyl propionate, 1,1,1-trichloro-2-methyl-2-butyl acetate, and 1,1,1-trichloromethyl-2-ethyl-2-butyl acetate.

It is understood that the preceding examples are representative and that they may be varied within the scope of the total specification disclosure, as understood and practiced by one skilled in the art, to achieve essentially the same results.

As many apparently widely different embodiments of this invention may be made without departing from the spirit and scope thereof, it is to be understood that this

invention is not limited to the specific embodiments thereof except as defined in the appended claims.

The embodiments of the invention in which an exclusive property or privilege is claimed are defined as follows:

5 1. A tetraalkyl lead antiknock-lead scavenger blend comprising a tetraalkyl lead and from about 0.2 to 1.0 theory of chlorine as a trichloromethyl substituted organic ester having the formula

10 where R is a C₁-C₂ alkyl and Ac is a C₁-C₃ acyl radical.

15 2. A tetraalkyl lead antiknock-lead scavenger blend comprising a tetraalkyl lead and from about 0.2 to 1.0 theory chlorine as 1,1,1-trichloro-2-methyl-2-propyl acetate.

20 3. A motor fuel composition comprising a mixture of hydrocarbons in the gasoline boiling range of which at least 15% by volume are aromatic hydrocarbons and which mixture of hydrocarbons has an octane rating of at least 80, an antiknock quantity of a tetraalkyl lead antiknock agent and from 0.2 to 1.0 theory of chlorine as a trichloromethyl substituted organic ester having the formula

25 where R is a C₁-C₂ alkyl and Ac is a C₁-C₃ acyl radical.

30 4. A motor fuel composition comprising a mixture of hydrocarbons in the gasoline boiling range of which at least 15% by volume are aromatic hydrocarbons and which mixture of hydrocarbons has an octane rating of at least 80, an antiknock quantity of a tetraalkyl lead antiknock agent and from 0.2 to 1.0 theory of chlorine as 1,1,1-trichloro-2-methyl-2-propyl acetate.

35 5. A tetraalkyl lead antiknock-lead scavenger blend comprising a tetraalkyl lead, from 0.5 to 1.0 theory of chlorine as a trichloromethyl substituted ester having the formula

40 wherein R is a C₁-C₂ alkyl and Ac is a C₁-C₃ acyl radical, and from 0.5 to 1.5 theories of halogen in the form of at least one halogen substituted hydrocarbon, wherein said halogen is taken from the group consisting of chlorine and bromine, with the proviso that not more than about 0.5 theory of said halogen is bromine and that said halogen substituted hydrocarbon acts as a scavenger for lead in combustion processes.

45 6. A tetraalkyl lead antiknock-lead scavenger blend of claim 5 wherein at least one of said halogen substituted hydrocarbons is an ethylene dihalide.

50 7. A tetraalkyl lead antiknock-lead scavenger blend of claim 5 wherein all of said halogen substituted hydrocarbons is ethylene dichloride.
